UNITED STATES PATENT OFFICE

127,491

DESIGN FOR A FINGER-REST CONTAINER

Gustav A. Rechlin, Chicago, Ill.

Application March 11, 1941, Serial No. 99,500

Term of patent 14 years

To all whom it may concern:

Be it known that I, Gustav A. Rechlin, a citizen of the United States, residing at Chicago, in the county of Cook and State of Illinois, have invented a new, original, and ornamental Design for a Finger-Rest Container, of which the following is a specification, reference being had to the accompanying drawing, forming part thereof.

I claim:

The ornamental design for a finger-rest container, as shown.

GUSTAV A. RECHLIN.
